UNITED STATES PATENT OFFICE.

LEON STEIN, OF PASSAIC, NEW JERSEY.

SHEET-METAL ROOFING.

No. 892,693.

Specification of Letters Patent.

Patented July 7, 1908.

Application filed August 17, 1907. Serial No. 389,081.

To all whom it may concern:

Be it known that I, LEON STEIN, a citizen of the United States, residing at Passaic, in the county of Passaic and State of New Jersey, have invented certain new and useful Improvements in Sheet-Metal Roofing, of which the following is a specification.

This invention pertains to certain new and useful improvements in sheet metal roofs, 10 and has for its object a roof construction which completely eliminates the use of wood as a support, and which provides a mode of joining or fastening the sheets which allows for expansion and contraction thereof.

15 In the accompanying drawings, Figure 1, is a top plan view of a portion of a roof equipped with my improved roof. Fig. 2, is a side elevation of two sheets illustrating the mode of connecting the same, Fig. 3, is a. 20 view in perspective showing the manner in which the sheets are joined, Fig. 4, is a similar view of one of the sheets looking up towards the under side thereof, Fig. 5, is an end elevation of the form of sheets used at the 25 apex of the gable portion of the roof, Fig. 6, is a perspective view of one of the sheets in detached position, and Fig. 7, is a plan view of one of the sheets employed at the roof corners.

30 In practice I employ sheets each of which is formed with an inverted U-shaped portion at one of its longitudinal sides formed by first bending metal upwardly at an incline as at D, then outwardly parallel with the body of the 35 sheet as at E, then downwardly at an incline as at F, and finally in turning over the longitudinal edge of the sheet as at G. The opposite longitudinal side edge of the sheet is bent upwardly at an incline and as at H, and 40 turned over on its longitudinal edge as at I.

As depicted in Fig. 3, the part H of one sheet enters into the space between the parts D F, of the adjacent sheet, thus forming a perfect water tight joint which freely permits 45 expansion and contraction of the parts without disrupting such joint.

The front portion J, of each of the front sheets A, is extended downwardly at an incline to the body of the sheet and is then 50 turned rearwardly as at K, to lie parallel with and but slightly spaced from portion J. Part K, is extended rearwardly parallel to and spaced from the under face of the sheet as at L, and is then bent in U-shape to pro-

vide pockets M, for receiving the securing 55 bars E. These bars E, are made of steel and of sufficient length to serve as connectors between the several sheets, which are disposed transversely to the length of the latter.

As clearly illustrated in Fig. 2, the adjacent sheets have their ends overlapping which is made possible by forming the rear sheets B, with their pockets for rod E, to the rear of the front edge thereof, clearly shown in Fig. 4. Thus it is obvious that the several 65 sheets A, and B are firmly secured to the rods E, and to one another.

Fig. 5, shows one of the form of sheets used at the apex of the gable, in this construction the sides C', C', are formed of an integral 70 piece of material and have the rod receiving pockets E', formed by extensions N which are turned under and extend rearwardly to lie parallel with the body of each side C' C', so as to locate pockets E', to the rear of the 75 lower ends of sides C', C'.

Fig. 7, shows one of the corner sheets D, which is formed with parts O and P similar to the inverted U-shaped parts of the sheets A and B and which overlap with the latter in 80 the same manner as shown in Fig. 2, wherein sheets A and B are so related.

It will be apparent that no wood whatever is involved in the construction. Moreover all fastenings of any nature are dispensed 85 with, with the exception of the metal bars E. At the same time the joints effected between the sheets are such that not only is a water proof union provided, but furthermore one wherein expansion and contraction of the 90 sheets may take place without injury to or disruption of the joints.

What is claimed is:—

In a metal roof, sheets each composed of a body having one of its sides inclined upwardly and having its edge turned over, and having its opposite side bent upwardly at an incline then outwardly to lie parallel with the body, and finally downwardly at an incline and having its free edge turned in, said first 100 named inclined side of one sheet extending in the space formed by the two inclined portions at the side of the adjacent sheet.

LEON STEIN.
